UNITED STATES PATENT OFFICE.

EDWARD SIEVART, OF MANITOWOC, WISCONSIN.

HEATING APPARATUS.

1,349,982.

Specification of Letters Patent. Patented Aug. 17, 1920.

Application filed March 29, 1919. Serial No. 286,205.

To all whom it may concern:

Be it known that I, EDWARD SIEVART, a citizen of the United States, and resident of Manitowoc, in the county of Manitowoc and 5 State of Wisconsin, have invented certain new and useful Improvements in Heating Apparatus; and I do hereby declare that the following is a full, clear, and exact description thereof.

10 My present invention has reference to new and useful improvements in hot air heaters, particularly to those which form units adapted for use in connection with furnaces and stoves of ordinary construction which 15 are already in operation.

It is well known that in all furnaces and stoves of typical design that more or less heat is wasted by allowing the hot gases to pass up the chimney before the major part 20 of the heat thereof can be extracted. The object of this invention, therefore, is to eliminate or reduce to a minimum this heat wastage. In carrying out this object a supplemental heater of unitary design is located 25 between the furnace, stove or the like and the chimney with which the same is connected.

It is also an object of the invention to provide a simply constructed heater of this 30 character which may be inexpensively manufactured of sheet metal, the parts being so arranged that the unit may be installed without material alterations in the parts with which it is to be associated.

35 A further object relates to provision of means for removing the soot and the like from the interior of the heating unit.

Other less important objects will become apparent as the description proceeds, in 40 which it will also be seen that the invention consists of certain novel features of construction, combination and arrangement of parts which are particularly shown in the drawings to which detailed reference will 45 be hereinafter made.

In the drawings:

Figure 1 represents a vertical sectional view of my improved heater unit, said section being taken substantially on the plane 50 of the line 1-1 of Fig. 2.

Fig. 2 is a horizontal section of the heater shown in the foregoing figure, the section being on the plane of the line 2-2 of Fig. 1.

Fig. 3 is a vertical sectional view of a 55 modification of the invention.

The essential characteristics of the inven-

tion are present in all four of the forms shown in the drawings and include an outer casing having an air inlet and outlet whereby cold air may be heated, an inner casing 60 disposed within the outer casing and so constructed with respect thereto that said air passes through and around the same, the heat laden gases from the furnace or stove being directed into the inner casing at one 65 side and led therefrom from the other side and into the chimney; a cleanout passage-way opens through the walls of the inner and outer casings so that soot and other deposits may be removed from the inner casing. 70 From the several figures of the drawing it will be evident that various changes may be made in the application of the invention without departing from any of the principles thereof.

75 Referring particularly to the structure illustrated in Figs. 1 and 2, 1 represents a heating unit for connection with medium draft furnaces and the like, it will be seen that the outer casing 1 is in the form of 80 a substantially rectangular box which is preferably formed of sheet metal, and that the same has a central opening in each of its vertical walls, said openings being designated respectively by the numerals 2, 3, 4 85 and 5. The inner casing 2' is also in the form of a rectangular sheet metal box and it is disposed within the outer casing 1, its sides being such that its walls are spaced from the walls of the outer casing to provide 90 an air space between the two casings.

An inlet pipe 6 extends through the opening 2 and has its inner end connected with the adjacent wall of the inner casing 2' for communication therewith. This inlet pipe 95 is designed to be connected with the stove or furnace pipe as the case may be. An outlet pipe 7 of similar construction extends through the opening 3 and has its inner end in communication with the interior of 100 the inner casing 2', said end being secured to the wall of the latter. The damper 8 of ordinary design is located in the outlet pipe 7 to control the passage of heated gases to the chimney with which it is directly or indirectly connected.

105 The air to be heated by the hot gases passing into the inner casing 2' is directed into the outer casing through an inlet pipe 9 secured in the opening 4, and after such air is heated it is led from the outer casing through the opening 5 with which an outlet pipe 10

is connected. In this particular form of my invention the air is not only directed around the inner casing, but also through the same, the latter being provided with a plurality of 5 air passageways for this purpose. Such passageways are formed by a plurality of cylindrical tubes 11 which are open at both ends and have such ends secured in openings in the top and bottom of the inner casing. Any 10 arrangement may be employed, but said tubes are preferably positioned in rows, the tubes of one row being staggered with respect to those of the other.

Inasmuch as the hot gases passing through 15 the inner casing contain more or less soot and the like, I provide means for readily cleaning the same periodically. The preferred arrangement includes one or more passageways 12 which bridge the space between 20 the walls of the inner and outer casings and are in communication with the former adjacent its bottom as shown in Fig. 1. Removable sliding covers 13 normally keep the passageways 12 closed to prevent 25 the escape of the hot gases.

The form of the invention illustrated in Fig. 3 is quite similar to the type shown in Figs. 1 and 2, but is adapted for use in connection with heavy draft furnaces and 30 stoves. The inner and outer casings, the inlet and outlet pipes for both of these casings, and the cleanout passageways are all substantially the same as set forth with respect to the other form. The air tubes which 35 extend through the inner casing 2^a are quite different from the tubes 11, however, they being rectangular in cross section and quite narrow in thickness as indicated at 11'. It will be noted that these tubes 11' are arranged in three horizontal rows, the middle 40 row being substantially in the plane of the longitudinal axis of the inlet and outlet pipes 6' and 7' respectively, the other two rows have their tubes so arranged that the passage of hot gases is considerably retarded in 45 its movement within the inner casing.

From the foregoing description and the several figures of the drawings it will be evident that I have devised a very simply 50 constructed and economical supplemental

heater which is capable of use with various types of furnaces and stoves, furthermore that the modification of the invention may be readily used with heating apparatus which has already been installed as well as 55 that which is yet to be placed in operation.

I claim:

1. A heating unit comprising an outer casing, an inner casing therein and spaced from the walls thereof, a plurality of parallel 60 rows of open ended fluid passageways disposed in the inner casing, their opposite ends being secured in the opposite sides of the inner casing to communicate with the space between the casings, the corresponding passageways of the several rows also forming parallel rows disposed in planes at right angles to the planes of the first mentioned rows, an inlet pipe extending through the outer casing and communicating with 70 the inner casing, an outlet pipe from the inner casing and extending through the outer casing, said pipes being adapted to convey hot gases through the inner casing, a fluid inlet into the outer casing, and a fluid outlet 75 from the outer casing.

2. A heating unit comprising an outer casing, an inner casing therein and spaced from the walls thereof, a plurality of parallel 80 rows of open ended fluid passageways disposed in the inner casing, their opposite ends being secured in the opposite sides of the latter to communicate with the space between the inner and outer casings, the passageways of one row being staggered with respect to 85 the passageways of the next adjacent rows, whereby to impede the passage of fluid through the inner casing, an inlet pipe extending through the outer casing and communicating with the inner casing, an outlet 90 pipe from the inner casing and extending through the outer casing, said pipes being adapted to convey hot gases through the inner casing, a fluid inlet into the outer casing, and a fluid outlet from the outer casing. 95

In testimony that I claim the foregoing I have hereunto set my hand at Manitowoc, in the county of Manitowoc and State of Wisconsin.

EDWARD SIEVART.
